UNITED STATES PATENT OFFICE.

MAGNUS V. BRÖNDUM, OF AARHUS, DENMARK.

POTATO COLLECTOR.

Application filed August 1, 1919. Serial No. 314,784.

To all whom it may concern:

Be it known that I, MAGNUS VILHELM BRÖNDUM, engineer, a subject of the King of Denmark, residing at Aarhus, Denmark, have invented some new and useful Improvements in Potato Collectors, of which the following is a specification.

My invention relates to a potato harvesting machine of the kind in which the materials are received by a movable grate, and consists essentially in the provision of serrated grate bars having a circular or elliptic motion imparted to them in a direction opposite to that of the road wheels of the machine, alternate bars being at a different angle of motion so that the materials are urged along the grates.

In the accompanying drawings the invention is illustrated,

20 Figure 1 representing a side view of one form of construction,

Fig. 2, a sectional rear view of the same, Fig. 3, a plan of the grates, and

25 Fig. 4, a cross-section of part of the grate on an enlarged scale.

Figs. 5 to 10 show side views of further modifications.

Fig. 11 represents a side view of the preferred form of the invention,

30 Fig. 12, a sectional rear view of Fig. 11, and

Fig. 13, a side view of another modification.

The machine frame 3 is carried by road wheels 1 mounted on a shaft 2 and provided with the usual draught pole 4. The shaft 2 is so connected to the wheels as to be compelled to rotate therewith, only when the machine moves in the forward direction.

40 The earth and potatoes are dug up by a share 5 having two side plates forming a share frame 6. The share frame 6 is supported by two arms 13 having journaled in their lower ends a shaft 11 which also ex-

45 tends through bearings 12 in the share frame 6. The inclination of the arms 13 is determined by stay rods 22 which engage at one end one of a series of apertures 27 in a plate 23 on the machine frame and at the

50 other end the arms 13. The forward end of the share frame 6 is suspended by means of links 32 on arms 31 secured to a rock-shaft 30. The adjustment of the share frame 6 and share 5 carried thereby, is ef-

fected by means of a hand lever 25 provided with the usual toothed segment 26 and having an operating arm 27 connected by means of a rod 28 to arm 29 on the rock-shaft 30.

The share 5 in being advanced along the ground delivers the materials dug onto an inclined moving grate comprising two sets of serrated bars 7 and 8, the movements of which are circular or elliptic in a direction opposite to that of the road wheels 1, and alternate so that the material is conveyed up the incline engaging with first one and then the other set. This movement, moreover, causes the earth to be separated from the potatoes and discharged through the spaces between the bars. The bar sets mesh with one another, two bars of each being preferably arranged close to one another, as shown in Figs. 3 and 4. The movements of the bars 7 and 8 are effected by means on the shaft 11 either by having each bar connected to a separate crank on the shaft, or, as shown in Fig. 4, by having the bars 7 supported by brackets 17 connected to a cross-bar 16 and the bars 8 of the other set connected by brackets 19 to cross-bars 18, the cross-bars 16 and 18 having arms 20 and 21 respectively, mounted on cranks of the crank shaft 11, the cranks of one set being disposed at an angle of 180° to the other. In this construction the front ends of the bars are supported on rollers 10 mounted on a shaft 9 carried by the share frame 6.

Some of the bars 7 and 8 are carried beyond the crank shaft 11 and incline in the opposite direction to form a delivery chute.

The crank shaft 11 receives its motion by means of a pinion 14 which meshes with a gear wheel 15 on the shaft 2.

In the construction according to Fig. 5 there is an additional shaft 34 which is driven by means of a chain gear 35 from the shaft 11 so as to move in unison with the latter. This shaft 34, serves as an additional support for the grate bars instead of the rollers 10 and causes the circular movement of the grates to be extended throughout their length. The cranks of this shaft 34 may be shorter than those of the shaft 11, the brackets 36, which support the bars thereon, being slotted to allow for the greater longitudinal movement imparted by the shaft 11 to the bars. A differential gear

38—39 is interposed between the pinion 14 and the gear wheel 15. The grates, the crank shaft, and the share 5 are carried by a frame 40 which is adjustable about the shaft 2 for varying the depth of the digging, the adjustment being effected by means of elements similar to those already described.

The crank shaft 34 may be omitted if the construction shown in dotted lines in Fig. 5 be adopted. According to this arrangement, there are two pairs of pivotally connected bars 41 and 43, one bar being connected by means of a link 42, and the other by a spring 44 to the frame 40. The bars 41 are also connected to and moved by a crank on the shaft 11, and the bars 43 support the forward ends of the grates by means of brackets 45. Operated by the crank shaft 11, these systems of levers cause the grates to move in a circular manner throughout their length.

The springs 44, which are neutral in the centre of their deflection movement will, at the ends of the movement, counteract the impetus of the grates and reduce the vibrations. The springs 44 are used instead of the rollers 10 shown in Fig. 1.

In Fig. 6 the forward ends of the grates are carried by springs 46 and 47 pivoted at diametrically opposite points to a disc 48 which can turn about a stud 49 on the frame 40. The disc 48 is rocked by the crank shaft 11 through the medium of a disc 52, a rod 51 connected to the disc 52 and a lever arm 50 connected to the disc 48. The disc 48 will thus impart an up-and-down movement to the forward part of the grates, the longitudinal movement being brought about by the crank shaft 11 directly. The arm 50 has a slot 53 by means of which its connection to the rod 51 can be varied relative to the stud 49 according to the extent of the movement desired. The springs 46 and 47 are rigidly connected to the grates.

In Fig. 7 the grates are carried entirely by springs similar to those just described which springs impart the up-and-down movement to the grates. This is effected by means of levers 54 carrying the springs and rocking about the pivots 49. The levers 54 have arms 56 interconnected by a rod 58 and one of them has an extension 59 which is acted upon by a crank 52 through the medium of a rod 60. The crank 52 is arranged above the grates and is driven from the shaft 2 by a system of beveled gears 63, 64, 65 and 66. The longitudinal movement of the grates is effected by the crank shaft directly through the medium of rods 61 and 62.

In Fig. 8 the grates are lengthened by rearward extensions 67 and 68 of a few bars working alternately behind each other and spaced so that the potatoes fall through while the haulm is carried further and dis-

charged sideways. The movement of the grates is effected in about the same manner as that described in connection with Fig. 6.

Fig. 9 shows the grates suspended on bars 71 and 72 which are operated by a crank shaft 11 and which engage studs 73 and 74 projecting from the cross bars 71 and 72. The forward ends of the grates may either be guided by rollers as shown in Fig. 1 or suspended as shown in Figs. 6 and 8. The crank shaft is arranged above the grate, and the haulm passes between the two. Underneath the grate extension is a chute 76 to receive the potatoes which can be delivered to either side of the furrow by turning the chute about a shaft 77 which carries the chute and is held by a bearing 78. The front part of the machine frame 75 rests on a small wheeled frame 79 and can be adjusted for depth by means of a hand lever 80.

In Fig. 10 a crank shaft 11 operates two double-armed levers 81 and 82 pivoted at 83 and 84 to bell-crank levers 85 and 86 which are pivoted at 87 to the frame 40. The lower ends of the levers 81, 82 hold the grates by means of links 71' and 72'. The forward ends of the grates are operated by springs 46, 47, levers 50 and rods 51 which latter are connected to the arms 88 of the levers 85, 86. In this case the grates are moved elliptically, and the movement can be varied by placing the pivots 83, 84 in different positions on the levers 81, 82.

In Figs. 11 and 12 the front parts of the grates are suspended by means of rods 81 and 82 on a crank shaft 11, and the rear part is suspended by means of rods 91, 92 from double-armed levers 85, 86 which are pivoted at 83, 84 to the middle portion of the rods 82 and 81 respectively. The levers 85, 86 must have their ends 89 and 90 connected so as to operate different sets of grates in order to make the ends of the grates move in the same direction. The pivots 87 of the levers 85, 86 may be connected to brackets 100 which are adjustable about a shaft 2 for varying the inclination of the grates. If no circular movement is to be imparted to the rear part of the grates, the arms 91, 92 may be connected to the frame 40, as shown dotted in Fig. 11, the levers 85, 86 being then dispensed with.

The grates are shown in Fig. 11 to have stepped formation, the rear part being on a lower level. The drop from the upper to the lower part of the grate adds to the shaking effect and facilitates the removal of the earth from the potatoes. The lower part may be made narrower or wider than the other, and the interstices between the bars may be varied as well. If the stepped formation of the grates be not desired the bars are run straight to the arms 91, 92 as shown in dotted lines 97 in Fig. 11.

- The grates may be constructed as shown in Fig. 12 in which the side bars are shown to be on a higher level than the middle ones so that the materials can be retained on the 5 grate without the frame 6. This may be effected either by lengthening some of the bar supports, by bending the cross-bars 16, 18 or by adding to the width of the outer bars.
- 10 According to Fig. 13 the grates are firmly secured by means of the studs 71, 72 to double-armed levers 81, 82 supported by a crank shaft 11. The pivots 83, 84 of the levers are held by the links 85', 86' the opposite ends of which are pivoted at 87 to a rigid arm 101 which also holds the share 33. The pivots 83, 84 may be adjusted for altering the movement of the grates. The working depth may be adjusted by means 20 of arms 102 movable about the shaft 2 and operated by means of a hand lever 104.
- The share may be dispensed with if the grates be extended in front and adapted to do the digging themselves. An elevator 25 may be employed for delivering the cleaned potatoes into sacks or into a trailer. The crank shaft may be operated by means of a separate motor instead of by the road wheels.
- 30 I claim:
1. In a potato harvesting machine of the character described having ground wheels, serrated grate bars, the serrated edges of the outer bars being at a higher level than 35 the serrated edges of the inner bars; and means for imparting a circular motion to said bars in a direction opposite to that of the ground wheels of the machine, alternate bars being at different angles of mo-
- tion so that the material is moved along 40 the grates.
2. In a potato harvesting machine of the character described having ground wheels, serrated grate bars; cross bars holding said 45 grate bars so as to form intermeshing grates; and means for imparting a circular motion to said grates in a direction opposite to that of the ground wheels of the machine, the grates being at different angles of motion so that the material is moved along 50 the grates.
  3. In a potato harvesting machine of the character described having ground wheels, serrated grate bars; cross bars holding alternate 55 grate bars so as to form two grates whose bars intermesh and work in pairs close to one another; and means for imparting a circular motion to said grates in a direction opposite to that of the ground wheels of the machine, the grates 60 being at different angles of motion so that the material is moved along the grates.
  4. In a potato harvesting machine of the character described having ground wheels, serrated grate bars; cross bars holding said 65 grate bars, so as to form intermeshing grates; cranks controlling the grates; and means for actuating the cranks so as to move the grates circularly in a direction opposite to that of the ground wheels of 70 the machine, the grates being at different angles of motion so as to convey the material thereon.

M. V. BRÖNDUM.
